UNITED STATES PATENT OFFICE

SAMUEL S. MATTHES, OF MANSFIELD, OHIO, ASSIGNOR TO THE OHIO BRASS COMPANY,
OF MANSFIELD, OHIO, A CORPORATION OF NEW JERSEY

SPLICER

Application filed July 6, 1931. Serial No. 548,941.

My invention relates to splicers particularly for trolley wires.

The object of my invention is to provide an efficient holding device for the butted ends of the trolley wire leaving the under surface free for the smooth and uninterrupted passage of the current collector.

My invention resides in the new and novel construction, combination and relation of the parts hereinafter described and shown in the accompanying drawings.

In the accompanying drawings:

Fig. 1 is a side view in elevation and partial section of my invention.

Fig. 2 is a section on the line 2—2 of Fig. 1.

Fig. 3 is a section on the line 2—2 showing the pin in holding relation with a trolley wire.

Fig. 4 is a view of the under side of a portion of the splicer without the wire in position.

My invention is an improvement upon that invention shown in Patent 1,773,193 issued 25 to me August 19, 1930.

I have found that it is desirable to provide means for preventing the insertion of the end pin into the wire to as great a depth as in the case of the other pins in order to 30 reduce the amount of distortion to which the trolley wire is subjected to upon the pin being forced therein.

My invention comprises a body member 1 with a plurality of transverse openings 2 in which are positioned preferably steel pins 3 and 4.

The pins are made with a sliding fit in the holes 2 and are provided with a reduced end 5 and a tapered end 6.

Along the upper edge of the splicer are 40 projecting flanges 7 and 8 which are normally as shown in Fig. 2, but after the pin has been forced into position by means of a tool as shown in my patent above referred to the flange takes the formation shown in Fig. 3 and interlocks with the tapered portion 6 of the pin, thus preventing the pin backing out.

In order to maintain all the pins of the same length which is desirable from the

manufacturers' and customers' standpoint, I provide bosses 9 surrounding the end pins 4 and which bosses are raised above the surface 10 of the splicer and these bosses 9 act as a seat against which the compressor tool 55 referred to contacts, thus limiting the amount of insertion of the pin into the wire. The difference to which the pins 3 and 4 may be forced into the wire is represented by the difference in the dotted lines at A. 60

This same result could of course be secured by making the pins 4 shorter than the pins 3, but this would mean the manufacture of two lengths of pins and the danger of the pins becoming intermixed, but 65 by the above described means the pins are all the same and the depth to which the pins may be forced into the trolley wire 11 is controlled by fixed means upon the splicer. 70

It will be recognized of course that the pins 3 next to the pins 4 may be arranged so as to force into the trolley wire a little greater distance than the pins 4 by surrounding the pins 3 with bosses of less 75 height than the bosses 9, but not as far as the third pins from the end.

Also the body may be tapered in height from a maximum at the end pins to a minimum at the inner pins. 80

The body is provided with a groove 12 along its lower edge to receive the trolley wires 11 and the lips 13 to prevent the displacement of the wire transversely.

In order to take care of the metal of the 85 trolley wire which is forced out of it, slight pockets 14 are formed opposite the passages 2 thus forming means to receive the forced out metal and also forming an interlock with the trolley wire to prevent in addition 90 to the pins the longitudinal displacement of the wire relative to the splicer.

It is desirable to have the trolley wire distorted as little as possible adjacent the end of the splicer and therefore by my improved 95 splicer I accomplish this result.

Having described my invention, I claim:

1. A wire splicer comprising an elongated body member, an open groove along one edge of the body to receive wires from both ends 100

- and inwardly projecting means to prevent the wires being displaced transversely of the groove, a plurality of means of uniform length slidably mounted in the body member and movable transversely of the axis of the wires to interlock with the wires to prevent the longitudinal movement of the wires in the groove, the said means being arranged in substantially alinement with their axes 5 and movable transversely of the axis of the wires to interlock with the wires to prevent the longitudinal movement of the wires in the groove, the said means being arranged in substantially alinement with their axes 10 in a plane coinciding with the axis of the connected wires and means surrounding each extreme end means to limit the insertion of the said end means into the wires to a less amount than the intervening means.
- 15 2. A wire splicer comprising an elongated body member, a groove to receive wires from both ends and means to prevent the wires being displaced transversely of the groove, a plurality of slidably mounted pins in the body between its ends to interlock with the wires below the surface thereof to prevent their longitudinal withdrawal and means to vary the depth relative to each other to which the pins interlock with the wires.
- 20 3. A wire splicer comprising an elongated body member, a groove to receive wires from both ends and means to prevent the wires being displaced transversely of the groove, a plurality of slidably mounted pins of uniform length in the body between its ends to interlock with the wires below the surface thereof to prevent their longitudinal withdrawal and means to reduce the depth to which the end pins interlock with the wires 25 as compared with the intervening pins.
4. A wire splicer comprising an elongated body member, a groove to receive wires from both ends and means to prevent the wires being displaced transversely of the groove, a plurality of slidably mounted pins in the body between its ends to interlock with the wires below the surface thereof to prevent their longitudinal withdrawal and means surrounding some of the pins to limit the 30 depth to which such pins interlock with the wires as compared with the other pins.
- 45 5. A wire splicer comprising an elongated body member, a groove to receive wires from both ends and means to prevent the wires being displaced transversely of the groove, a plurality of slidably mounted pins of uniform length in the body between its ends to interlock with the wires below the surface thereof to prevent their longitudinal withdrawal and means surrounding some of the pins to vary the depth to which such pins interlock with the wires as compared with the balance of the pins.
- 50 6. A splicer comprising a body member having a longitudinal groove along one edge, a pair of wires positioned in the groove with their ends adjacent, inwardly projecting means along the splicer to engage the wires to prevent their displacement transversely of the groove, a plurality of slidably mounted

pins in the body arranged to interlock with the wires to different depths to prevent the displacement of the wires longitudinally.

7. A splicer comprising a body member having a longitudinal groove along one edge, 70 a pair of wires positioned in the groove with their ends adjacent, inwardly projecting means along the splicer to engage the wires to prevent their displacement transversely of the groove, a plurality of slidably mounted pins in the body arranged to interlock with the wires to prevent the displacement of the wires longitudinally and means to control the interlock of the pins in the wires to 75 different depths.

8. A splicer comprising an elongated body member having a longitudinal groove along one edge to receive trolley wires, inwardly projecting means to engage the wires to prevent their displacement transversely of the body, a plurality of pins slidably mounted in the body to interlock with the wires, the pins being alined along the axis of the wires, and means to vary the depth of interlock of the pins with the wires.

9. A wire splicer comprising a body member to receive the wires to be spliced with a portion of the longitudinal surface of the wires exposed, a plurality of pins slidable in a transverse direction to the axis of the wires to interlock to varying depths with the surface of the wires opposite the exposed surface.

10. A wire splicer comprising a body member to receive the wires to be spliced with a portion of the longitudinal surface of the wires exposed, a plurality of pins slidable in a transverse direction to the axis of the wires to interlock with the surface of the wires opposite the exposed surface and means along one side of the body member to control the interlock to varying depths.

In testimony whereof I affix my signature.
SAMUEL S. MATTHES.
